UNITED STATES PATENT OFFICE.

RAY L. CARTER, OF SYRACUSE, NEW YORK.

ADJUSTABLE CUTTER HEAD.

Application filed June 19, 1924. Serial No. 721,045

To all whom it may concern:

Be it known that I, RAY L. CARTER, a citizen of the United States, residing at Syracuse, in the county of Onondaga and State 5 of New York, have invented certain new and useful Improvements in Adjustable Cutter Heads, of which the following is a specification.

This invention relates to improvements in 10 cutter-heads, designed for holding the tools carried by the rotatable spindles of shapers, routers, and milling-machines, and has for its object to provide novel and simple means for clamping and adjustably holding a plurality of cutters rigid to the shaft or spindle, which rotates the head.

A further object is to provide a cutter-head for shapers and the like, comprising 15 spaced discs or collars, between which the cutters may be clamped, said discs being movable towards and from each other for accommodating cutters of different lengths, as well as two or more cutters disposed end to end; said discs being slideable on the spindle 20 and on guide-posts that parallel the spindle, the said posts passing axially through the cutters.

A further object is to provide novel means 25 for adjusting the guide-posts radially relatively to the spindle, for regulating the depth of cuts made by the cutters while the head is being rotated, as well as for maintaining the normal depth of the cuttings when the cutters are reduced in diameter by 30 grinding or wearing away; the said adjusting means being arranged to position the posts and cutters relatively to the axis of rotation, as well as to each other, for effecting uniform cutting by the several spaced 35 cutters.

And a further object is to provide an adjustable head of the class, by which tools having cutting-blades of different shape, contour and diameter may be applied to each 40 guide-post, for effecting fancy or ornamental cuts.

The various features and parts of the invention will be understood from the detailed description which follows, and by reference 45 to the accompanying drawing, in which—

Figure 1 is a top-plan view of the stationary table, above which the adjustable cutter-head is positioned. Fig. 2 is a broken side elevation and central vertical section; the 50 section being taken on line 2—2 of Fig. 1.

Fig. 3 is a face view of the uppermost disc. Fig. 4 is a face view of the adjusting disc. Fig. 5 is a horizontal section, taken on line 5—5 of Fig. 2. Fig. 6 is a top-plan view of the cutter-head shown in Fig. 1. Fig. 60 7 is a plan view of the adjustable disc of Fig. 4; showing the disc rotated in the direction for effecting the maximum adjustment of the cutters and their supports. Fig. 8 is a horizontal section, similar to Fig. 65 5; showing the relative positions of the cutter-supporting posts, when the adjusting disc is rotated, as shown in Fig. 7. Fig. 9 is a central vertical section, similar to Fig. 2; 70 showing an assembly of several pairs of cutters for effecting ornamental cuts. And Fig. 10 is a plan view; showing the differently shaped cutters of Fig. 9.

In the drawing, 2 represents the usual stationary circular table of a portable shaping 75 machine, which supports the work, and 3 the power-driven shaft; the top end of said shaft which projects above the table, preferably being reduced and threaded, as at 3', to receive a clamping nut 3^a.

My improved cutter-head comprises similar top and bottom discs or collars 4 and 5, both of which are provided with smooth-bore central openings, as 4'—5', to receive the spindle 3' of the shaft, and said discs have similar oppositely arranged radial slots, as 4^a—5^a. The discs 4—5 are partially supported, and are held from independent rotary movement on the spindle 3', by similar guide-posts 6, which are disposed 85 in the corresponding slots 4^a—5^a, parallel to the spindle; the said posts being adjustably mounted on pins 7, the latter being driven tightly into radial holes 5^b 90 of the lowermost disc, which align with and span the slots 5^a, as shown in Figs. 1, 5 and 8. The posts 6 are slideable on the pins 7 by means of holes 6', for effecting their adjustment radially, as may be understood by 95 comparing Figs. 2 and 8. The adjustment of the posts 6 is effected by a disc or plate 8, which is bored out centrally to receive the spindle 3', upon which it rotates, and said disc preferably rests upon the collar 5. The disc 8 is provided with similar eccentric slots 8', through which the posts 6 pass, and by means of which said posts may be moved towards and away from the spindle 3'. The disc 8 is also provided with similar concentric oppositely arranged slots 8^a, through 100

105 110

which set-screws 8^b are inserted, and then screwed into the collar 5, for holding the disc 8 in various adjusted positions.

Referring to Figs. 1, 2, 9 represents one form of standard cutters, which are used in connection with my adjustable head. These cutters are preferably arranged in pairs, and each is provided with four or five integral arms or blades 9', which are disposed substantially tangent to the axes of the cutters, as shown in Figs. 1 and 10. The cutters 9 are all bored out centrally to receive the posts 6, and one or more of the cutting blades 9' project beyond the peripheries of the collars 4-5 and the disc 8, as best seen in Figs. 1 and 2. The depths of the shaping or routing cuts are regulated by the extent of this projection, and may be increased or decreased, by the rotation of the disc 8, for effecting the radial movements of the guide-posts 6, as explained. Ordinarily, but one of the blades 9' of each cutter performs the shaping work, and when the head is rotated at high speed, these oppositely arranged single blades 9' effect extremely smooth cuts. In case one of the blades 9' becomes broken, or worn away by grinding until it is too short to effect the required cut, the operator removes the nut 3^a, and the collar 4, and slides the defective cutter upwardly on its post 6 until it is free from the spindle and post. The operator may then restore the broken or worn cutter to the post, in a manner to dispose one of the remaining perfect blades 9' in the cutting position, as shown. In this way, the cutters may be shifted or readjusted from time to time, until all of the blades are worn out. The cutters 9 are shown mounted upon the disc 5, and are held rigidly in place by the disc 4 and nut 3^a, as shown in Figs. 1, 2 and 6. By this construction and arrangement, the disc 4 serves as a guide and support for the free top-ends of the posts 6, and also performs the function of a clamping washer; and when the nut 3^a is screwed down tightly, the cutters and clamping parts are held rigidly against the shoulder 3^b of, and are rotatable as one part by, the shaft 3. Any tendency of the cutters 9 to rotate on the posts 6, due to extraordinary strains induced by the work, is overcome by the corresponding inwardly facing idle blades 9', which closely straddle the spindle 3', as shown in Fig. 1.

In Fig. 5 the dotted circles indicate the normal diameters of the cutters of Figs. 1 and 2 when new. As the blades of the cutters naturally become shorter, due to frequent grinding, it becomes necessary to move the cutters outwardly, in order to effect the normal depths of the cuts. This may be accomplished readily, quickly and accurately, by the following means: The operator first loosens the nut 3^a and set-screws 8^b, and then

rotates the plate 8, as from the position shown in Figs. 1 and 4, to that shown in Fig. 7. This effects the outward radial movement of the posts 6, as shown in Fig. 8, from which it may be seen that, even though the cutters 9 have been ground or worn away to a relatively great extent (see dotted circles Fig. 8), their cutting blades may still effect the same relative depth of cut. By the same method of adjustment, new cutters of relatively small diameters may be operatively applied to the head and perform their work.

In Fig. 9 is shown three cutters mounted upon each post 6, wherein the uppermost and lowermost tiers correspond in shape and size, and whose cutting edges 9^a are of the same contour; while the middle tier, comprises cutters having convex blades, as shown in Fig. 2. When several differently formed cutters are thus applied to the posts 6, a great variety of fancy or ornamental cuts may be effected in a ready and simple manner.

My improved cutter-head is extremely simple, and not only effects a great economy in the operation and maintenance of the shapers, but includes several novel and desirable features of adjustment and convenience, not heretofore known and used. The present device comprises relatively few parts, all of which are readily accessible, and are not liable to wear out or become impaired or rendered inaccurate by ordinary shop use. Furthermore, my cutter-heads do not require skilled operators, but may turn out satisfactory work, when operated by the well-known "handy" men usually employed in industrial plants.

Having thus described my invention, what I claim, is—

1. In a cutter-head, the combination with a stationary table, a driven threaded spindle, and a pair of similar cutters said cutters being bored out axially, of a pair of similar collars having registering radial slots adjustably mounted on said spindle, said collars adapted to be spaced for receiving therebetween the said cutters, means for moving said cutters, means engaging the bores of the cutters and said radial slots for controlling the cutters radially relatively to said spindle, and means for clamping the collars to said spindle.

2. A cutter-head, including a threaded spindle, circular centrally perforated members mounted on said spindle, said members having corresponding radial slots, cutters disposed between said members having radial cutting-blades adapted to be successively projected beyond the peripheries of said members and having central openings adapted to register with the said slots, guide-posts mounted for radial movement in said slots and passing axially through said cut-

ters, means interposed between said members for adjusting said cutters radially relatively to the spindle, and means for clamping said members to said spindle.

5 3. A cutter-head including a threaded spindle, circular centrally perforated members mounted on said spindle, said members having corresponding radial slots, cutters disposed between said members having radial cutting-blades adapted to be successively projected beyond the peripheries of said members and having central openings adapted to register with the said slots, guide-posts mounted for radial movement in said 10 slots, pins carried by the lowermost member for adjustably supporting said posts, means interposed between said members for adjusting said cutters radially relatively to the spindle, and means for clamping said members to said spindle.

4. A cutter-head including a threaded spindle, spaced circular members adjustably mounted on said spindle, said members having oppositely disposed radial slots, cutters bored out axially disposed between said members, the bores of said cutters registering with the slots of said members, posts passing through said slots and said cutters, a rotatable disc disposed concentrically between said members and having eccentric slots to receive said posts adapted for moving the posts radially relatively to the spindle for varying the depths of the cuts effected by said cutters, and means for clamping said members and related parts rigidly to said spindle for movement as one part.

5. The combination with a stationary table, a power-driven spindle projecting above the table, and a plurality of cutters each formed with a number of cutting blades, of a pair of perforated collars spaced to receive said cutters mounted on said spindle and having corresponding radial slots disposed at the opposite sides of the spindle, guide-posts disposed in said slots parallel to the spindle and passing axially through the corresponding cutters, means for moving said posts radially relatively to each other for varying the depths of the cuts effected by said blades, means for adjustably securing said posts in the slots of one of said collars, and means for clamping said collars to the spindle and for preventing rotation of the cutters on said posts.

55 6. The combination with a power-driven shaft having a reduced threaded spindle, and a pair of axially bored cutters having radial cutting blades, of a pair of circular clamping members mounted on said spindle adapted to be spaced to receive said cutters therebetween, said members having oppositely arranged radial slots adapted to register with the bores of the cutters, guide-posts passing through said members and said cutters, radially disposed pins carried

by the lowermost member and passing loosely through said posts, means for moving said posts on said pins radially relatively to said spindle for varying the depth of the cutting work of said blades, and means for tightly clamping said cutters and said members together and for effecting the rotation of said parts by said shaft.

7. The combination with a stationary work table, a driven shaft passing through said table and having a threaded spindle projecting above the table, and a pair of cutters having central openings and having radial cutting blades adapted to effect the cutting work, of a pair of similar perforated discs 75 mounted concentrically on said spindle adapted to be spaced for receiving therebetween the said cutters, said discs having corresponding radial slots registering with the openings in said cutters, guide-posts passing axially through said cutters and through the slots of said discs parallel to said spindle, pins spanning the slots in the lowermost disc upon which said posts are slidable, means for moving said posts and cutters radially, and means for clamping said discs and said cutters together for operation by said spindle as one part.

8. The combination with a power-driven shaft having a reduced threaded spindle at 95 one end, of a cutter-head comprising a pair of circular perforated clamping members of the same diameter disposed one above the other on said spindle, said members having corresponding oppositely arranged radial slots, radial pins spanning the slots of the lowermost member, guide-posts slidably mounted on said pins and extending through the corresponding slots of said members, a disc perforated centrally for receiving said spindle mounted on the lowermost member, said disc having eccentric slots through which said posts pass and by means of which said posts may be moved radially relatively to said spindle, means for locking and holding said disc in various adjusted positions, a cutter mounted concentrically on each post and having radial cutting blades, one blade of each cutter adapted to

100 project beyond the peripheries of said members for effecting the cutting work, said cutters adapted to be shifted on said posts for successively bringing the several blades into the cutting position, and means for clamping said members to the spindle and for holding said cutters from rotation on said posts.

9. The combination with a shaft having a reduced threaded spindle at one end, of a cutter-head comprising circular flat perforated members adapted to be adjustably mounted one above the other on said spindle, said members having corresponding radial slots, axially bored cutters disposed between said members and having a plurality of ra- 115 120 125 130

dial cutting blades adapted to be successively extended beyond the opposite margins of the members, the bores of said cutters registering with the corresponding slots of the members, a disc perforated centrally to receive the spindle disposed between said members, said disc having eccentric slots adapted to register substantially with said slots and with the bores of the cutters and having concentric slots, screws passing through said concentric slots and threaded

into the adjacent member, guide-posts passing through the slots of the members, said disc, and the corresponding cutters, means for slidably securing the lower ends of said posts in the slots of the lowermost member, and a nut applied to the free end of said spindle for clamping the members tightly to said spindle and to said cutters. 15

In testimony whereof I affix my signature.

RAY L. CARTER.
